FRAME FOR FIRE SCREENS, ETC.

Leland M. Burr, Jr., Lincoln, Mass., assignor to
Cutter Manufacturing Company, Cambridge,
Mass., a corporation of Massachusetts

Application April 26, 1937, Serial No. 138,952

16 Claims. (Cl. 189—36)

This invention relates to frames for firescreens, license plates, mirrors and other articles of the type comprising longitudinal and transverse members interconnected to form a rectangular frame with slots in their opposing faces to receive the firescreen or other article to be mounted therein.

Objects of the invention are to provide a frame which is rigid and durable in construction, which can be readily assembled and disassembled, which is neat and attractive in appearance, and generally to improve frames of the type to which the present invention relates.

Other objects of the invention will be evident from the following description and accompanying illustration of typical embodiments of the invention in which

Fig. 1 is an elevation of a two-section fire-screen;

Fig. 2 is a similar view, parts being shown in section and parts broken away;

Figs. 3 and 4 are detail sectional views of modifications;

Fig. 5 is a section on line 5—5 of Fig. 3;

Fig. 6 is a section on line 6—6 of Fig. 4;

Fig. 7 is an inside face view of the longitudinal frame member of Figs. 3 and 5;

Fig. 8 is a similar view of the longitudinal member of Figs. 1 and 2;

Fig. 9 is a detailed sectional view of still another modification; and

Fig. 10 is an end view of the modification of Fig. 9.

The particular embodiment of the invention shown in Figs. 1, 2 and 8 comprises longitudinal frame members 1, transverse frame members 2, screen sections 3, hinge straps 4 and a tie rod 5. The longitudinal members 1 have slots 6 in their inner faces, these slots terminating short of the ends of the members and having enlargements 7 at their extremities. The transverse frame members 2 have slots 10 extending throughout their full lengths on their inner faces. The screen sections 3 comprise longitudinally and transverse rods 8 and 9 integrally joined together at the corners with the wire mesh of the screens mounted over these rods. The longitudinal rods 8 have extensions 11 and 12 at their upper and lower ends extending through openings 13 in the ends of the transverse frame members 2.

Threaded on the ends of the projecting portions 11 and 12 are nuts 14 and 15. The nuts 14 have tapered portions 16 telescoping inside the tubes 1 to center the nuts in the tubes; and the nuts 15 have cylindrical portions similarly telescoping

into the tubes. At the lower and upper ends of the two central longitudinal frame members the nuts 17 telescope entirely inside the tubes with the rods 8 extending therethrough to serve as pintles for the hinge pieces 4. The two hinge pieces are tied together by the rod 5 which threads into the lower hinge member and receives a nut 18 at its upper end.

To assemble the parts of the embodiment shown in Figs. 1, 2 and 8 the transverse frame members 2 are first fitted over the top and bottom of the screen sections with the projecting portions 11 and 12 of the rods 8 projecting through the openings 13 in the ends of the transverse frame members. The longitudinal frame members 1 are then fitted over the sides of the screen sections with the ends of the transverse member 2 fitting into the enlarged ends 7 of the slot 6 in the inner faces of the longitudinal frame members. In the case of the upper outer corners of the frame, where the portions 11 project a considerable distance above the upper transverse members 2 the longitudinal frame members 1 may first be hooked over the projecting portions 11, with the lower ends of these frame members extending outward at an angle, the members then being simultaneously moved downwardly and swung inwardly until they reach the position shown in Figs. 1 and 2. Near the end of this swinging movement the screen is lifted until the cross rods 9 touch the top of the inner peripheries of the transverse tubes 2 thereby to permit the lower end of the slot 6 to pass under the lower end of rod 8.

The modification shown in Figs. 3 and 5 differs from that shown in Figs. 1, 2 and 8 in that the longitudinal frame member 1' has a slot extending throughout its full length as shown at 6' in Fig. 7 and in that the nut 14 is replaced by a nut 14' which has an annular groove to receive the end of the frame member 1', with a peripheral flange 20 which covers the upper end of the slot 6'. Whereas the nut 14 seats on the end of the longitudinal frame member with clearance between the nut and the end of the transverse frame member 2, the nut 14' seats on the end of the transverse frame member 2 with clearance between the end of the longitudinal frame member 1' and the bottom of the annular groove in the nut.

The modification shown in Figs. 4 and 6 comprises rectangular frame members 21 and 22 instead of circular frame members as in the preceding figures. With this type of construction a filler piece 23 is preferably fitted into the ends of

the longitudinal frame member 21 underneath the nut 24. The filler piece 23 preferably has the same polygonal cross section as that of the longitudinal frame member 21.

5 In the modification shown in Figs. 9 and 10 the polygonal filler 23' is recessed to receive the nut 24' so that the nut does not project.

It should be understood that the present disclosure is for the purpose of illustration only and 10 that this invention includes all modifications and equivalents which fall within the scope of the appended claims.

I claim:

1. A frame for firescreens and other articles 15 comprising longitudinal and transverse frame members one of which is provided with an inwardly facing slot, a portion of the slot being enlarged to receive the end of the second of said members, said end having an opening extending therethrough within and lengthwise of the first member, a rod extending lengthwise within said first member and having a portion projecting through said opening, and means interfitting with said projecting portion and with 20 the end of said first member for securing the parts together.

2. A frame for firescreens and other articles comprising longitudinal and transverse frame members one of which is provided with an inwardly facing slot to receive a central section extending into the slot, a portion of the slot being enlarged to receive the end of the second of said members, said end having an opening extending therethrough within and lengthwise 30 of the first member, means having a portion projecting through said opening for mounting said section in the frame, and means interfitting with said projecting portion and with the end of said first member for securing the parts together.

3. A frame for firescreens and other articles comprising longitudinal and transverse tubular frame members provided with inwardly facing slots to receive a central section extending into 45 the slots, one of said members having a portion of its slot enlarged to receive the end of the second of said members, said end having an opening extending therethrough within and lengthwise of the first member, means having a portion projecting through said opening for mounting said section in the frame, and means interfitting with the end of said first member for securing the parts together, said last means including a part fitting over said projecting portion and seating against said end of the second member.

4. A frame for firescreens and other articles comprising longitudinal and transverse tubular frame members provided with inwardly facing 60 slots to receive a central section extending into the slots, one of said members having a portion of its slot enlarged sufficiently to receive the end of the second of said members, said end having an opening extending therethrough within and lengthwise 65 of the first member, means having a portion projecting through said opening for mounting said section in the frame, and means for securing the parts together, said last means including a part fitting over said projecting portion and a surface telescoping with the end of said first member and a surface seating against said end of the second member.

5. A frame for firescreens and other articles comprising longitudinal and transverse frame members one of which is a cylindrical tube pro-

vided with an inwardly facing slot to receive a central section extending into the slot, a portion of the slot being enlarged to receive the end of the second of said members, said end having an opening extending therethrough within and lengthwise of the first member, means having a portion projecting through said opening for mounting said section in the frame, and a nut threaded on said projecting portion and snugly telescoping with the end of said first member and seating against said end of the second member.

6. A frame for firescreens and other articles comprising longitudinal and transverse frame members one of which is a polygonal tube provided with an inwardly facing slot to receive a central section extending into the slot, a portion of the slot being enlarged to receive the end of the second of said members, said end having an opening extending therethrough within and lengthwise of the first member, means having a portion projecting through said opening for mounting said section in the frame, and means for securing the parts together, said last means including a polygonal piece telescoping with the end of said first member and seating against said end of the second member and a nut threaded on the end of said projecting portion and seating against said piece.

7. A frame comprising pairs of longitudinal and transverse frame members, the members of each pair being opposite each other and one pair having opposing slots to receive a central section extending into the slots, portions of said slots being enlarged to receive the ends of the members of the second pair, said ends having openings extending therethrough within and lengthwise of the members of the first pair, a rod extending through each of the members of the first pair with portions projecting through said openings, and means for securing the parts together including nuts threaded on the ends of said portions.

8. A frame comprising pairs of longitudinal and transverse frame members, the members of each pair being opposite each other and one pair having opposing slots terminating short of the ends of the members to receive a central section extending into the slots, the extremities of said slots being enlarged to receive the ends of the members of the second pair, said ends having openings extending therethrough within and lengthwise of the members of the first pair, a rod extending through each of the members of the first pair with portions projecting through said openings, and means for securing the parts together including nuts threaded on the ends of said portions and surfaces telescoping with the ends of the members of said first pair.

9. A frame comprising pairs of longitudinal and transverse tubular frame members, the members of each pair being opposite each other and having opposing slots to receive a central section extending into the slots, the members of one pair having portions of their slots enlarged to receive the ends of the members of the second pair, said ends having openings extending therethrough within and lengthwise of the members of the first pair, a rod extending through each of the members of the first pair with portions projecting through said openings, and means for securing the parts together including nuts threaded on the ends of said portions.

10. A frame comprising pairs of longitudinal and transverse tubular frame members, the mem-

bers of each pair being opposite each other and having opposing slots to receive a central section extending into the slots, the members of one pair having their slots terminating short of their ends and the extremities of their slots enlarged to receive the ends of the members of the second pair, said ends having openings extending therethrough within and lengthwise of the members of the first pair, a rod extending through each of the members of the first pair with portions projecting through said openings, and means for securing the parts together including nuts threaded on the ends of said portions.

11. A frame comprising pairs of longitudinal and transverse tubular frame members, the members of each pair being opposite each other and having opposing slots to receive a central section extending into the slots, the members of one pair having portions of their slots enlarged to receive the ends of the members of the second pair, said ends having openings extending therethrough within and lengthwise of the members of the first pair, a rod extending through each of the members of the first pair with portions projecting through said openings, and means for securing the parts together including parts fitting over the ends of said rods and surfaces telescoping with the ends of the members of said first pair.

12. A frame comprising pairs of longitudinal and transverse tubular frame members, the members of each pair being opposite each other and having opposing slots to receive a central section extending into the slots, the members of one pair having their slots terminating short of their ends and the extremities of their slots enlarged to receive the ends of the members of the second pair, said ends having openings extending therethrough within and lengthwise of the members of the first pair, a rod extending through each of the members of the first pair with portions projecting through said openings, and means for securing the parts together including parts fitting over the ends of said rods and surfaces telescoping with the ends of the members of said first pair.

13. A frame for firescreens and other articles

comprising longitudinal and transverse frame members one of which is provided with an inwardly facing slot, a portion of the slot being enlarged to receive the end of the second of said members, said end having an opening extending within the first member, and means extending lengthwise within said first member and having a portion within said opening for securing the parts together.

14. A frame for firescreens and other articles comprising longitudinal and transverse frame members one of which is provided with an inwardly facing slot to receive a central section extending into the slot, a portion of the slot being enlarged to receive the end of the second of said members, said end having an opening within the first member, and means interfitting with said opening and with the end of said first member for securing the parts together.

15. A frame comprising pairs of longitudinal and transverse frame members, the members of each pair being opposite each other and one pair having opposing slots to receive a central section extending into the slots, portions of said slots being enlarged to receive the ends of the members of the second pair, said ends having openings extending therethrough within and lengthwise of the members of the first pair, and means for securing the parts together including means disposed within the members of said slotted pair and extending into said openings of the other pair.

16. A frame comprising pairs of longitudinal and transverse tubular frame members, the members of each pair being opposite each other and having opposing slots to receive a central section extending into the slots, the members of one pair having portions of their slots enlarged to receive the ends of the members of the second pair and the members of the first pair having projecting ends extending beyond the members of the second pair longitudinally of the members of the first pair, and means for securing the parts together including surfaces in telescopic interengagement with said projecting ends.
